SAFETY CLOTHESLINE PULLEY

Filed April 4, 1928

UNITED STATES PATENT OFFICE

ALFRED E. VAUTHIER, OF NEW YORK, N. Y.

SAFETY CLOTHESLINE PULLEY

Application filed April 4, 1928. Serial No. 267,290.

This invention relates to pulley line holders and in particular to one of the safety type which may be swung into the room preparatory to hanging out or removing 5 clothes on the line.

A particular object of the invention is to provide a simplified safety clothes line pulley carrying arm which may be swung into the room and which will permit the 10 clothes to be placed on the line without the necessity of the housewife leaning out of the window.

A still further object of the invention is to provide in a device of this character, a 15 locking member which will effectively lock the pulley in its inwardly swung position so that the weight of the clothes on the line will not have a tendency to swing the pulley to a position exterior of the window.

20 A still further object of the invention and an important one, is the provision of means in connection with a device of this character whereby when the device is swung pivotally to a position exterior of the window, 25 the line carried thereby will not be tautened by reason of its being folded upon itself but will be moved about a pin with a wrapping movement so that the line will not be placed under tension with subsequent 30 harm to the clothes pole to which the line is attached, at its outer end.

A still further important object of the invention is to provide a means for mounting a safety clothes line pulley so that it can, when swung into the room, be disposed 35 in substantial alignment with the clothes line itself.

To enable others skilled in the art to 40 fully comprehend the underlying features of my invention that they may embody the same in the various modifications in structure and relation contemplated, a drawing depicting a preferred form has been annexed as a part of this disclosure and in 45 such drawing, similar reference characters denote corresponding parts throughout all the views, of which,

Figure 1 is a view in perspective of my improved safety clothes line pulley showing 50 how the same is positioned within a room to

permit the taking in or the hanging out of clothes.

Figure 2 is a view in side elevation of the device illustrated in Figure 1, the same being shown swung into position to permit 55 the taking in or hanging out of clothes.

Figure 3 is a view in end elevation of the device as illustrated in Figure 2, the view being taken from the outer end of the device and being shown partly in section to 60 show how the arm carrying member may be locked in any one of a number of desired pivotal positions, and

Figure 4 is a top plan view of the device, the swinging movement thereof being illustrated in outline to show how the pulley line will be wrapped around a suitable pin member so that tautening thereof is prevented.

Figure 5 is a view in elevation showing 70 the sliding bolt arrangement.

Referring to the drawings in detail, 5 indicates the wooden sash frame of a window construction, the portion thereof exterior of the sashes being indicated by the numeral 75 6 and being arranged to support the standard or base 7 of the safety clothes line pulley construction, the same being secured to the sash frame portion 6 through the medium of suitable screws 8.

This base member is provided with the upstanding ears 9 which are spaced apart to receive the tongue 10 of a bracket member, the same being pivoted relatively to the base through the medium of a bolt 11 which 85 passes through the ears 9, one of the latter of which is provided with an enlarged opening 12 to receive the nut 13 which effectively locks said tongue 10 between the ears 9 and prevents free pivotal rotation of the 90 bracket. By loosening up on the head of the bolt 11, the bracket 10 may be swung to any position so that a pulley carrying arm carried thereby may be positioned longitudinally of the line. The bracket is provided with the spaced portions 14 which have cast integral therewith spool-like extensions 15 constituting posts having enlarged outer edges 16 which prevent the line from slipping over the ends thereof. 100

These spool-like extensions are positioned at one corner of the extensions 14 of the bracket and are so arranged that the enlarged outer extremities will overlie the strands of the pulley line when the pulley carrying arm is extended into the room but permitting the line to disengage from the extension for its free movement to draw in the clothes or to hang the same outside the window.

The device further consists of a pulley carrying arm 17 which is provided with the reinforcing ribs 18, the free end of the arm terminating in a bifurcated portion 19 in which is pivotally supported the pulley 20, the outer periphery of the pulley being covered through the medium of a suitable guard 21 which is secured in any suitable manner to the end 19 of the pulley carrying arm. The opposite end of the arm 18 is enlarged as at 22 and fits snugly within the projection 14 of the bracket and is hinged therein through the medium of the hinge pin 23 which permits pivotal rotation of the arm 18 within the bracket.

In order to lock the arm when it is drawn into the room, I have provided a bolt 24, one end of which is upturned as at 25 to permit engagement by the hand to withdraw or otherwise manipulate the bolt, the bolt being secured in slidable relation to the arm through the medium of the pin and slot connection 26, the bolt being further guided by a guide eye 27 which is cast or otherwise secured to the pulley carrying arm 18. One side of the enlarged end 22 of the arm 18 is flattened and spaced from the wall of the bracket and this space permits the bolt 24 to be slid between the end 22 of the arm and the bracket thus preventing accidental rotation of the arm 18 when the same has been swung into position within the room to permit removal or hanging out of the clothes.

In Figure 4, it will be noted that the pivot pin 23 is so situated relatively to the spool-like extension 15 that when the arm 18 is swung to a position outside the window, this swinging position being noted by outline in Figure 4, that the clothes line 27 will be wrapped about said extension 15.

In devices of this character heretofore employed, the pivotal movement of the swinging arm has caused the line to be placed under tension with the result that any dampness causes a still further tension in the line and the pulley holding hook is either drawn out of the clothes pole or else the clothes pole itself is loosened. In the use of my device, it will be evident that the bolt 24 acts as a safety device in that it will not permit the arm 17 to swing outward until the bolt is withdrawn. Also, in my improved device, the use of a pivoted bracket which may be locked in any

angular position relatively to the base, permits the arm 17 to be disposed at all times in longitudinal alignment with the line 27 thus decreasing wear of the line and always maintaining the same in proper position within the pulley 20, thus facilitating the hanging out or removal of the clothes therefrom.

It is evident also that when the arm 17 has been drawn into the room for removal of the clothes, the line 27 can be released from its connection with the spool-like extension 15 of the bracket and the clothes can be removed therefrom with a minimum of effort and time.

It is evident, therefore, that my device provides for the safe hanging of clothes on a pulley line, that it eliminates any necessity for the housewife leaning out of the window and also it provides for adjustment of the pulley holding arm so that the position of the clothes pole relative to the window is immaterial and once the bracket is set in its angular position relatively to the base, it need not be removed nor further adjusted.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention what I claim as new and desire to secure by United States Letters Patent is:

A clothes line safety device comprising a base, a bracket, a bolt joining said base and bracket and permitting adjustable movement of the latter, spaced extensions on the bracket, a pulley arm having an end disposed between said bracket extensions, one side of the arm being spaced from a side of said bracket, a pivot pin connecting the bracket and arm to permit swinging movement of the latter, a bolt on the arm slidably into the space between the arm and the bracket to prevent swinging movement of the arm and a post on each of said bracket extensions to be engaged by the clothes line.

In testimony whereof I affix my signature.

ALFRED E. VAUTHIER. [L. S.]
